DESIGN FOR A HINGE UNIT

James Orville Willard, Cleveland Heights, Ohio,
assignor to The Mills Company, Cleveland,
Ohio, a corporation of Ohio

Application January 14, 1936, Serial No. 60,579

Term of patent 7 years

To all whom it may concern:

Be it known that I, James Orville Willard, a citizen of the United States, residing at Cleveland Heights, in the county of Cuyahoga and State of Ohio, have invented a new, original, and ornamental Design for a Hinge Unit, of which the following is a specification, reference being had to the accompanying drawing, forming part thereof.

Fig. 1 is a top perspective view of the upper

portion of the hinge unit; Fig. 2 is a side perspective view of the upper hinge unit; Fig. 3 is a top perspective view of the lower portion of the hinge unit; and Fig. 4 is a side perspective view of the lower portion of the hinge unit,—all showing my new design.

I claim:

The ornamental design for a hinge unit, as shown.

JAMES ORVILLE WILLARD.
